ATTORNEY

UNITED STATES PATENT OFFICE

WILLIAM H. QUADE, OF LOS ANGELES, CALIFORNIA

PLASTER AND STUCCO REINFORCING BASE

Application filed August 1, 1927. Serial No. 209,787.

My invention relates to a metal lath base, or a reenforcing base, or foundation, for supporting and reenforcing plaster, stucco, or other plastic material.

8 The objects of my invention are: first, to provide a base of this class having substantially rigid reenforcing and spacing means applied to a sheet backing for reenforcing the backing and the plaster, or other plastic material, applied on the same and for spacing a wire netting at all portions from the sheet backing; second, to provide a base of this class in which the reenforcing means substantially rigidly supports the base to the 18 studs of a wall and prevents the sheet backing to which the reenforcing means is secured from bulging inwardly, thus, rigidly reenforcing the plastic material applied on the same and also providing a uniform thickness of the plastic material on the base; third, to provide a base of this class in which the plastic material applied on the same is uniformly reenforced throughout and rigidly supported on the studding of the wall on 25 which the base is secured; fourth, to provide a base of this class which may be easily and rigidly secured to the studs, or other supporting means on the wall, by merely securing the reenforcing means thereto; fifth, to 30 provide simple and unitary means for securing poultry netting, or other wire netting, and the reenforcing means to a paper backing; sixth, to provide a base of this class in which staples, or other means, for securing 35 the netting and reenforcing strips to the paper or other sheet backing are covered on the inside of the wall so as to prevent moisture from deteriorating the staples or other securing means; seventh, to provide a base 40 of this class which, by reason of its construction, may be readily rolled and sold in rolls; eighth, to provide a base of this class which may be readily applied to the studs, or other supporting means of a wall by applying the 45 long sheet longitudinally with and to the studs so that the edges thereof overlap and provide continuous reenforcing, the transversing reenforcing and spacing strips forming reenforcing means transversely to the 50 studs; ninth, to provide reenforcing and spac-

ing strips for a base of this class to which wire netting of different mesh may be secured; and, tenth, to provide, as a whole, a novelly constructed base of this class and one which is simple and economical of construction, durable, easy and efficient of application and which will not readily deteriorate.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon which form a part of this application in which:

Figure 1 is a fragmentary elevational view of a skeleton building wall, showing a fragmentary portion of my base secured thereto over a plurality of studs and also showing adjacent edges of adjacent sheets of the base overlapped; Fig. 2 is an enlarged view thereof; Fig. 3 is a sectional view thereof, taken on the line 3-3 of Fig. 2 and in the direction of the longitudinal extent of the sheet when rolled; Fig. 4 is an enlarged sectional view thereof, taken through 4-4 of Fig. 2, showing the means for securing the netting and reenforcing and spacing strips to the sheet backing; and, Fig. 5 is a perspective view of my backing in a roll.

Like characters of reference refer to similar parts and portions throughout the several views of the drawings.

My reenforcing base, or foundation, for plaster, stucco, or other plastic material, consists essentially of a paper backing 1, reenforcing and spacing strips 2, wire netting 3, staples 4, a second or inner paper backing 5, and adhesive material 6.

The paper backing 1 provides the main support of my base and may be made of a relatively light weight of building paper, such as asphalt felt, or other waterproof felt, or craft paper. When the base is rolled, the sheets are of considerable length and of such a width as to extend over several studs, indicated by 7 in Fig. 1. The reenforcing strips 2 are made of sheet metal of channel

100

shaped cross-section with the outer edges of the side flanges thereof provided with laterally and oppositely directed flanges 2a. These strips are positioned with their narrower portions, or bottom portions of the channel shape, against the normally outer side of the paper backing 1. These strips extend transversely to the longitudinal extent of the paper when the same is adapted to be 5
rolled and extend to substantially the edges of the paper, as shown. These strips also extend parallel to each other and are spaced apart at a certain distance depending upon the mesh of the wire netting used. The wire 10
netting 3, as shown in the drawings, is a conventional poultry netting and positioned lengthwise over and at the outer side of the paper backing 1 and is spaced therefrom by the strips 2 against the outer sides or the outer 15
sides of the flanges 2a on which the netting is secured. The netting and the strips 2 are secured to the paper backing by staples 4 which extend outwardly from the back side of the paper backing and through spaced 20
holes in the channel portion of the strips 2. The outer ends of the staples 4 are bent toward each other and around portions of the netting, as shown best in Figs. 2 and 4. The holes 2b in the strips 2 through which the 25
staples 4 extend are so arranged that poultry netting of different mesh may be secured to the same strips. In order to prevent moisture at the inside of the wall from having any deteriorating effect on the metal portions 30
of the base or particularly on the portions of the staples at the inner side of the paper backing 1, I have provided a covering 5 at the inner side of the paper backing 1. This covering 35
5 may be of the same material as the backing or sheet 1 and may be secured to the back side thereof by any suitable plastic material 6.

One edge of the wire netting is spaced inwardly from one edge of the paper backing 45
1, while the opposite edge of the netting extends beyond the opposite edge, as shown best in Figs. 1 and 2, so that the extended edge of the netting of the adjacently positioned base strip overlaps the paper backing and 50
reenforcing strip of the adjacently positioned backing strip, as shown best in Fig. 1. The base is applied to the studding 7 by nails or staples which extend through the reenforcing strips. When staples are used, the same 55
may secure simultaneously the reenforcing strips, as well as the adjacent edges of the netting, as shown in Fig. 1.

The base above described may be readily 60
rolled, as shown in Fig. 5, the netting and the paper yielding sufficiently to permit rolling and also to permit unrolling to assume their desired spaced relations, as shown in Fig. 3, in which the netting 3 is shown as spaced uniformly from the paper backing or 65
support.

Though I have shown and described a particular construction, combination and arrangement of parts and portions, I do not wish to be limited to this particular construction, combination and arrangement, but desire to include in the scope of my invention 70
the construction, combination and arrangement substantially as set forth in the appended claims.

Having thus described my invention, what 75
I claim as new and desire to secure by Letters Patent is:

1. In a plaster or stucco base, a paper backing, reenforcing strips positioned in spaced relation on the outer side of the paper backing and extending transversely thereto, wire netting positioned at the outer side of said paper backing and secured to the outer sides of said reenforcing strips and spaced by said strips from said paper backing, and unitary means securing said wire netting to said reenforcing strips and to said paper backing, said means securing also said reenforcing strips to said paper backing. 80

2. In a plaster and stucco base, a paper backing, reenforcing strips positioned in spaced relation on the outer side of the paper backing and extending transversely thereto, wire netting positioned at the outer side of said paper backing and secured to the outer sides of said reenforcing strips and spaced by said strips from said paper backing, means securing said wire netting through said reenforcing strips to said paper backing, said means securing also said reenforcing strips to and through said paper backing, and a second paper backing adhesively secured to the back side of the first paper backing for covering the portions of the securing means extending to the back side of the first paper 95
backing. 100

3. In a plaster or stucco base, a paper backing, reenforcing strips positioned in spaced relation on the outer side of the paper backing and extending transversely thereto, wire netting positioned at the outer side of said paper backing and secured to the outer sides of said reenforcing strips and spaced by said strips from said paper backing, and a second paper backing adhesively secured to the 110
back side of the first paper backing. 115

4. In a base of the class described, a sheet backing, channel shaped reenforcing strips spaced from each other and extending across said sheet, a yieldable wire netting positioned at the outer side of said sheet and secured against the outer side of said reenforcing strips, and staples securing said netting to said sheet through the bottom of the channel shaped reenforcing strips. 120

5. In a base of the class described, a sheet backing, channel shaped reenforcing strips spaced from each other and extending across said sheet, a yieldable wire netting positioned at the outer side of said sheet and secured 125
130

against the outer side of said reenforcing strips, staples securing said netting to said sheet through the bottom of the channel shaped reenforcing strips, and a waterproof covering applied at the inner side of said sheet and over the staples extending therethrough.

6. In a base of the class described, a backing sheet of flexible and freely bendable material, reenforcing strips of channel shaped cross-section positioned in parallel spaced relation at the outer side of said sheet and extending thereacross with the bottom of the channel against said sheet, the outer flanges 15 of said strips being provided with laterally and oppositely directed flanges substantially parallel with and spaced from said sheet, and yieldable wire netting positioned at the outer side of said sheet against the outwardly and 20 oppositely directed flanges of said reenforcing strips and secured thereto.

7. In a base of the class described, a backing sheet of flexible material, reenforcing strips of channel shaped cross-section positioned in parallel spaced relation at the outer side of said sheet and extending thereacross with the bottom of the channel against said sheet, the outer flanges of said strips being provided with laterally and oppositely directed 30 flanges substantially parallel with and spaced from said sheet, yieldable wire netting positioned at the outer side of said sheet against the outwardly and oppositely directed flanges of said reenforcing strips, and wire 35 staples securing said wire netting to the outer sides of said reenforcing strips and extending through the bottom of the channel portions thereof and through said backing sheet.

8. In a base of the class described, a long 40 flexible sheet backing adapted to be rolled, a plurality of reenforcing and spacing strips secured to the normally outer side of said sheet in transverse relation to the length of the sheet and parallel to the axis of the sheet 45 when rolled, poultry netting secured to said reenforcing and spacing strips and spaced from said sheet and adapted to be rolled therewith, and unitary staples extending through said backing sheet, said reenforcing and spacing strips and around said netting for securing the strips and netting to said sheet.

9. In a base of the class described, a long 55 flexible sheet backing adapted to be rolled, a plurality of reenforcing and spacing strips secured to the normally outer side of said sheet in transverse relation to the length of the sheet and parallel to the axis of the sheet 60 when rolled, poultry netting secured to said reenforcing and spacing strips and spaced from said sheet and adapted to be rolled therewith, staples extending through said backing sheet, said reenforcing and spacing strips and around said netting for securing the strips and netting to said sheet, and a water-

proofing applied to the opposite side of said sheet for covering the portions of the staples extending to the back side thereof.

10. In a base of the class described, a long 70 flexible sheet backing adapted to be rolled, a plurality of reenforcing and spacing strips secured to the normally outer side of said sheet in transverse relation to the length of the sheet and parallel to the axis of the sheet when rolled, poultry netting secured to said reenforcing and spacing strips and spaced 75 from said sheet and adapted to be rolled therewith, staples extending through said backing sheet, said reenforcing and spacing strips and around said netting for securing the strips and netting to said sheet, a waterproofing applied to the opposite side of said sheet for covering the portions of the staples 80 extending to the back side thereof, and a waterproof paper adhesively secured to the back side of said sheet.

In testimony whereof, I have hereunto set my hand at Los Angeles, California, this 14th day of July, 1927.

WILLIAM H. QUADE.
